(57) **CLAIM**

The ornamental design for a discharge device, as shown and described.

DESCRIPTION

FIG. 1 is a right side view of a discharge device in accordance with our new design;

FIG. 2 is a left side view thereof;

FIG. 3 is a top perspective view thereof;

FIG. 4 is a front view thereof;

FIG. 5 is a rear view thereof;

FIG. 6 is a top view thereof; and,

FIG. 7 is a bottom view thereof.

The broken lines depict portions of the discharge device in which the design is embodied that are not considered part of the claimed design.
